UNITED STATES PATENT OFFICE

2,313,959

MECHANICAL RELAY

Gunnar Nelson, Dayton, Ohio, assignor to The National Cash Register Company, Dayton, Ohio, a corporation of Maryland

Original application January 21, 1938, Serial No. 186,107. Divided and this application June 26, 1941, Serial No. 399,931

13 Claims. (Cl. 74—1)

This invention relates to a mechanical relay or control transmitting means for transferring the setting of certain groups of elements to other groups of elements.

This application is a division of the application for United States Letters Patent, Serial No. 186,107, which was filed by Gunnar Nelson on January 21, 1938, and which issued on January 27, 1942, as Patent No. 2,270,960.

It is often desirable to transfer the setting of certain elements to other elements after the certain elements have been set and to be able to do this without adding the load of setting the other elements to the means which sets said certain elements.

It is an object of this invention to provide a means for transferring controlling representations from one set of elements to another.

Another object of the invention is to provide means for setting a second element according to the setting of a first element without requiring the setting means for the first element to set both elements.

A further object of this invention is to provide a power-operated means operable, after certain elements have been set to indicate a control, to transmit the control indication to other elements.

Another object of this invention is to provide a transmitting means which is operable to successively transmit a plurality of control indications during a single transmitting operation.

Another object of this invention is to provide a means for simultaneously transmitting a control from one plurality of elements to another plurality of elements, in which the side spacing of the elements of the different plurality of elements need not be uniform.

Another object of the invention is to provide an internally-gearied, laterally-moving transmitting means whereby the same transmitting means can be moved laterally and associated successively with several control devices, making it unnecessary to have a separate transmitting device for each control device.

With these and incidental objects in view, the invention includes certain novel features of construction and combinations of parts, the essential elements of which are set forth in appended claims and a preferred form or embodiment of which is hereinafter described with reference to the drawing which accompanies and forms a part of this specification.

In said drawing:

Fig. 1 is a plan view of the transmitting means

and a portion of the settable elements with which it cooperates.

Fig. 2 is a right side elevation of the transmitting means, showing in particular the driving means for shifting the transmitting means laterally.

Fig. 3 is a side elevation of the transmitting means, showing in particular the means for oscillating the transmitting means.

General description

The transmitting means or mechanical relay is used to transfer the setting of preset groups of plates or elements to other related groups of plates or elements. It consists of a laterally-shiftable unit having a forwardly-extending arm for each group of preset plates and a corresponding rearwardly-extending arm for each of the other related groups of plates, which arms are connected by internal gearing for joint movement.

The unit is shifted laterally, step by step, to positions opposite the plates of the groups and in each position is oscillated to transfer the setting from the preset plate to the other related plate. The preset plates may occupy either a lower or an upper position according to the control to be exerted, and, if the plate is in its upper position, the complete oscillation of the forwardly and rearwardly extending arms is blocked, and the other related plate is not shifted; but, if the preset plate is in its lower position, the forwardly-extending arm will be allowed to make a complete oscillation, and the connected rearwardly-extending arm will cause the other related plate to be shifted. In this manner, each set of interconnected arms can be successively operated to transfer the setting of the several preset plates of a group to a related group of plates.

Detailed description

As explained fully in the above-mentioned Patent No. 2,270,960, two groups of plates 361 (Figs. 1, 2, and 3) are provided, which plates may be selectively set to occupy an upper or a lower position to represent data. The data representations of the groups of plates 361 are transmitted to related groups of plates 296 to enable these last-mentioned plates to control the machine. Inasmuch as the details of the means for setting the plates 361 and the manner in which the plates 296 exert their control are not necessary for an understanding of the present invention, they will not be described herein, and reference may be had to said Patent No. 2,270,960 for these details if further information is desired.

The means for transmitting data from the groups of plates 361 to their related groups of plates 296 will now be described.

Referring to Figs. 2 and 3, it will be seen that each of the plates 361 has, extending rearwardly, a step 396 and that the position of each plate, whether raised or lowered, may be judged according to whether its step is in the raised or the lowered position.

The transmitting means which conveys the position of each of the plates 361 to the corresponding plates 296 consists of a forwardly-extending lever 397 (Figs. 1, 2, and 3) for each of the two groups of plates 361; a hub 398 for each lever 397, on which each lever is rotatably mounted; a shaft 399, on which the hubs are secured; a corresponding lever 400 for each lever 397, said levers 400 extending rearwardly; individual hubs 398 on which each lever 400 is rotatably mounted; a yoke 402 for each set of levers 397 and 400; plates 403 secured to the shaft 399, to which the yokes 402 are fastened; springs 404 holding each lever 397 and 400 in yielding contact with its yoke; and shafts 417 and 418 for connecting levers 397 with their corresponding levers 400.

The transmitting means, which transmits data representations from the plates 361, which comprise groups of settable plates, to their related plates 296, which also form groups of plates, is adapted to accommodate different side spacing of the various groups of plates, the groups of plates 296 in lateral disposition in the machine being spread out, while the groups of plates 361 are close together.

Shaft 399 (Fig. 1) is shiftable laterally in bearings 405 and is also rotatable. The lateral movement of said shaft is supplied under positive control by roller cam follower 406, pinned to shaft 399, moving in a circumferential groove 407 in drum cam 408, which cam is secured on a rotatable shaft 410 and, at the proper time in each machine cycle, makes a complete rotation in a counter-clockwise direction, as viewed from the right side. Fig. 1 shows the cam 408 in rest position and also the shaft 399 in the extreme left position or rest position. Dividing into degrees the drum cam's circumference, the groove 407, during the first 30 degrees of the cam's rotation, forces the shaft 399 to the extreme right position, said movement being exactly that required to shift levers 397 across the four plates 361 from the IV plate to the I plate (Fig. 1) in their respective groups. The rotation from the thirtieth to the ninetieth degree of the circumference of cam 408 causes no lateral motion to shaft 399. From the ninetieth to the 120th degree, the shaft is moved to the left sufficiently to move the levers 397 to the II plate of each group. The shaft remains laterally stationary from the 120th degree to the 180th degree on the cam. From the 180th degree to the 210th degree, the shaft moves to the left again, so that levers 397 are opposite the III plate of each group; then there is no lateral movement until the shaft is moved between the 270th degree and the 300th degree to the extreme left, so that levers 397 are opposite the IV plate of each group. During the periods when levers 397 are not in lateral motion—namely, the next sixty degrees of rotation after the 30th, 120th, 210th, and 300th degrees—the shaft 399 is rocked counter-clockwise, then clockwise, as viewed from the right, by means of positive drive double plate cam 409 (Figs. 1

and 3), which is secured to shaft 410, as is cam 408 (Fig. 1). Cam followers 411 (Figs. 1 and 3) are rotatably mounted on studs extending from the ends of bell crank lever 330 (Fig. 1) pinned to shaft 399. The cam followers are also slidably mounted on their supporting studs to allow for the lateral motion of shaft 399.

The means for rotating cam shaft 410 is shown in Fig. 2. Shaft 70, rotating twice each machine cycle, has pinned to it a gear 69 driving gear 67, pinned to shaft 68, once every cycle of operation. Gear 412, rotatably mounted on stud 413 projecting from the frame, is driven once every machine cycle by gear 100, which is also pinned to shaft 68. Hubbed to gear 412 is a mutilated gear 414 designed to impart intermittent motion to Geneva wheel 415. The Geneva wheel is rotated by the mutilated gear 414 once every machine cycle between the 220th and the 360th degrees and is locked in the usual manner by the Geneva stop consisting of a concave projection on the intermittently-driven gear 415 and a convex perimeter on the mutilated gear 414.

The shaft 399, as has been shown, by moving bodily the hubs 398, the levers 397 and 400, the yokes 402, and the plates 403, positions levers 397 (Fig. 1) in the plane of each of the four plates 361 of its related group of plates in succession, once each machine operation. Each time the levers 397 stop in the plane of a plate 361, the shaft, as explained, makes a rocking motion on its long axis, turning plates 403 and yokes 402 first counter-clockwise, then clockwise, as viewed from the right side. Levers 397 tend to follow the yoke 402 counter-clockwise, due to the tension of springs 404. Referring to Fig. 2, it is evident that, if plate 361 is raised, its rearwardly-extending step 396 will prevent lever 397 from following the yoke 402. If a plate 361 is in a down position, the lever will follow the yoke until its end hits the step. Thus the lever 397, as it moves along its four positions, feels the position of each plate 361, which, if raised, causes more relative motion between the hub 398 and the lever 397 than if the plate is in the down position.

It is desired that, whenever there is relative motion between levers 397 and their hubs 398, the levers 400 have the same relative motion; therefore each lever 397 is geared to its corresponding lever 400 in such a manner that the movements of levers 397 around hubs 398 positively move levers 400 in the same direction about their hubs, each pair of levers 397 and 400 being movable independently of the other pair of levers and representing a group of plates 361 and 296, respectively.

The system of gearing disclosed in United States Patent No. 1,693,279 issued to Walter J. Kreider is used to achieve the desired paired movement of levers 397 and 400 and consists of internal gearing, which will now be described. Hubs 398 are furnished for each lever 397 and 400, making four in all. Each hub near the periphery has ten small holes 419 and one large hole 420, whose centers are equally spaced radially and circumferentially around shaft 399. The radii on which the holes of one hub are positioned are aligned with the same radii in the other three hubs. The hubs for each pair of levers 397 and 400 have their large holes 420 in alignment, no two pairs being at the same place on the circumference. Two shafts 417 and 418, one shaft for each group of settable plates, are inserted through these holes, leaving eight un-

used holes in each hub. In this machine, only two pairs of levers being used, representing two groups of settable plates, only two shafts are used. The remaining eight positions illustrate the expansibility of this system to accommodate a machine of more than two groups of settable plates 361. By using more holes in the hubs, the system may be correspondingly expanded.

Referring to Fig. 1, the shaft 418 has secured thereon two gears 416 and 424, gear 416 lying within the large hole in the circumference of hub 398 of lever 397, which analyzes the left-hand group of settable plates 361, and gear 424 lying in the large hole in the circumference of hub 398 of lever 400, actuating the plates 296 corresponding to this group of settable plates 361. In a similar manner, the shaft 417 has secured thereon two gears 422 and 423 connecting the other lever 397 and lever 400, transmitting the position of the right-hand group of settable plates 361 to the related plates 296. The inside bearing surface of levers 397 and 400 are toothed to engage the teeth of the gears 416, 422, 423, and 424. Fig. 2, showing the hub of the lever 400 actuating the left-hand group of plates, will serve to illustrate the principle of operation of the other internal gears. If either lever 397 is moved in relation to its hub, its companion lever 400 will move to the same extent and to the same distance against the urge of its spring 404. Reference may be made to the above-mentioned Kreider patent if further explanation is desired.

The plates 361, the levers 397, the levers 400, and the plates 296 are so positioned that, if, upon oscillation of shaft 399, the levers 397 strike raised plates 361, their companion levers 400 will not contact forwardly-projecting toes 421 (Figs. 2 and 3) of plates 299, whereas, if any plates 361 are not raised, the companion levers 400 will contact toes 421 on the corresponding plates 299, turning them clockwise. Four plates 299 are provided for each group of plates 296 and are pivotally supported on a stub shaft 298 (Figs. 1 and 3) projecting from one of the frame plates, where they are held from lateral movement on the shaft by collars 300. There is a plate 299 for each plate 296. Rearwardly projecting from each plate 299 is a lug 302 (Fig. 3), fitting into a rounded notch 297 formed in the lower end of its corresponding plate 296, so that rotary movement of the plate 299 moves its plate 296, a clockwise movement of plate 299 causing a downward movement of plate 296 and vice versa. The plates 296 are restricted in their motion by studs 263 and slots 301, and, as plates 299 are rotatable only to the extent that lugs 302 can move with notches 297, it follows that plates 299 are restricted in their rotary motion. On the periphery of each plate 299 are two notches 303 and 304 adapted to be engaged by a spring-pressed positioning pawl 305. The pawls 305 allow the plates 299 to assume their most clockwise position when engaged in notch 304 and their most counter-clockwise position when engaged in notch 303. A plate 299 can be in only one of the two positions. This means that plates 296 must be in either their lowest position or their highest position and will be yieldingly held there. In Fig. 3, the plates 296 are shown in their lowest position and the plates 299, therefore, in their clockwise position.

All of the plates 296 must first be in the upper position before a transmitting operation can take place. A resetting yoke 306 (Figs. 1 and 3), securely mounted on shaft 298, is adapted to turn

plates 299 to their counter-clockwise position by means of the bail of the yoke engaging projecting shoulders 307 of plates 299 when shaft 298 is turned counter-clockwise. The means for giving the counter-clockwise motion to shaft 298 includes a lever 308 (Fig. 1) pinned to the left end of the shaft 298 and pivotally connected by link 309 to an operating means which is fully disclosed in the above-mentioned Patent No. 2,270,960.

Thus it is seen that the transmitting means can cooperate simultaneously with two or more groups of settable plates 361 and successively sense the position, whether upper or lower, of the corresponding plates of each group. Whenever one of the settable plates 361 is in the upper position, the forwardly-extending arm 397 will be arrested and stop the rearwardly-extending arm 400 before it can rock the plate 299 and shift the plate 296 from the position to which it was reset by the bail of the yoke 306 engaging the projection 307 on the plate 299. If a plate 361 is in a lower position, the arm 397 will not be arrested, but will travel to its farthest extent of movement and will cause its connected lever 400 to engage and rock the plate 299. The rocking of the plate 299 will cause the plate 296 to be shifted from its reset position. Since the settable plates 361 represent data by their raised or lowered position, the transmitting means, by shifting the plates 296 to positions corresponding to those of the plates 361, transfers the data to the plates 296 in order that these plates can control the machine according to this data.

The novel means, therefore, provides a compact means which successively senses the preset position of the plates or elements of a group and transmits this setting to plates or elements of another group. However, this novel means is not limited to transferring data from a single group of elements to another, for, with this means, the elements of a plurality of groups may be sensed simultaneously and the settings transferred to elements of other corresponding groups of elements. It should also be noted that, with the novel transmitting means, it is not necessary for the groups of elements from which data is transferred to have the same side spacing as the groups of elements to which the data is transferred, because the use of the internal gearing enables any desired side spacing of the various groups of elements to be obtained. A further advantage of the transmitting means resides in the fact that a setting means utilizing a small force can set the preset elements, and the transmitting means, being power-operated, can operate after the preset elements have been set and can transfer the setting to other elements without placing the burden of operating the other elements on the means which sets the preset elements.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In an apparatus of the class described, the combination of a plurality of elements presettable to represent a control; a corresponding plurality of control elements settable according to the setting of the presettable elements; and

power-operated means operable after the presettable elements have been set and successively cooperable with corresponding presettable elements and control elements for setting the control elements according to the setting of the presettable elements.

2. In an apparatus of the class described, the combination of a plurality of presettable elements which, by their setting, indicate a control condition; a corresponding plurality of settable control elements; transmitting means for transferring the setting from the presettable elements to the corresponding plurality of elements; means to move the transmitting means successively into position to cooperate with corresponding presettable and control elements; and means to operate the transmitting means in each of said positions to transmit the setting of the presettable elements to the control elements to thereby transfer the control condition to the control elements.

3. In an apparatus of the class described, the combination of a first plurality of settable elements for representing data by their setting; a second plurality of settable elements; a laterally shiftable oscillatable transmitting means intermediate the first plurality of settable elements and the second plurality of settable elements for transferring data from the first to the second plurality of elements; and power-operated means for shifting the transmitting means laterally to associate it successively with corresponding elements in the first and second plurality of elements and for oscillating it each time it is associated with a pair of elements to transfer the setting from the element of the first plurality of elements to the corresponding element of the second plurality of elements, whereby the data represented by the first plurality of elements is transferred to the second plurality of elements.

4. In a machine of the class described, in combination, a shaft; means to rock the shaft on its axis; means to shift the shaft to and fro on its axis; a plurality of hubs secured to said shaft; a lever rotatably mounted on each hub; means to adjust the levers rotatably on their hubs without varying the relative angular disposition between selected pairs of said levers; a plurality of yokes designed to confine the rotation of selected pairs of the levers on the hubs to certain limits; and means for yieldingly holding said selected pairs of levers at their limit of motion in one direction.

5. In a machine of the class described, in combination, a shaft rockable and shiftable; hubs secured to the shaft; a lever rotatably mounted on each hub; means to transmit the rotary motion of one lever to another lever whether adjacent or not; and means to confine the rotation of the levers within certain limits.

6. In a machine of the class described, in combination, a plurality of sets of levers; a shaft on which said levers are rotatably mounted; means for shifting the shaft; means for rocking the shaft; and an internal gearing means for rotating the levers of a selected set to a like extent.

7. In a machine of the class described, in combination, a shaft shiftable and rockable; a means to shift the shaft on its axis step by step in one direction and uninterruptedly in the other direction; means to rock the shaft in a complete oscillation after each shifting movement; a plurality of hubs secured on said shaft; levers rotatably mounted on said hubs, the bear-

ing surface of the levers having internal gear teeth; interior gears cooperating with the internal gear teeth on the levers; and rods inserted in perimetricaly-positioned clearance holes in the hubs joining the interior gears of selected levers whereby adjacent or non-adjacent levers may be moved with a fixed angular relation between them.

8. In a machine of the class described, in combination, a shaft shiftable and rockable; a means to shift the shaft step by step in one direction and uninterruptedly in the other direction; means to rock the shaft in a complete oscillation after each shifting movement; a plurality of hubs secured on said shaft; levers rotatably mounted on said hubs, the bearing surface of the levers having internal gear teeth; interior gears cooperating with the internal gear teeth on the levers; rods inserted in perimetricaly-positioned clearance holes in the hubs joining the interior gears of selected levers whereby adjacent or non-adjacent levers may be moved with a fixed angular relation between them; and yokes limiting the rotation of the levers on the hubs within certain limits.

9. In a machine of the class described, in combination, a shaft; means to rock the shaft on its axis; means to shift the shaft to and fro parallel to its axis; two hubs secured to said shaft; a lever rotatably mounted on each hub; and means to move the levers rotatably on their hubs without varying their relative angular disposition thereon.

10. In a machine of the class described, in combination, a shaft; means to rock the shaft on its axis; means to shift the shaft to and fro on its axis; a plurality of hubs secured to said shaft; a lever rotatably mounted on each hub; and means to move selected pairs of levers rotatably on their hubs without varying the relative angular disposition between the levers of a pair.

11. In a machine of the class described, in combination; a shaft; means to rock the shaft on its axis; means to shift the shaft to and fro on its axis; a plurality of hubs secured to said shaft; a lever rotatably mounted on each hub; means to move the levers rotatably on their hubs without varying the relative angular disposition between selected pairs of said levers; and means to yieldingly hold the levers in a fixed position on their hubs.

12. In a machine of the class described, in combination, a shaft shiftable and rockable; a means to shift the shaft step by step in one direction and uninterruptedly in the other direction; means to rock the shaft in a complete oscillation after each shifting movement; a plurality of hubs secured on said shaft; levers rotatably mounted on said hubs; the bearing surface of which have internal gear teeth; interior gears cooperating with the internal gear teeth on the levers; rods inserted in perimetricaly-positioned clearance holes in the hubs joining the interior gears of selected levers whereby adjacent or non-adjacent levers may be moved with a fixed angular relation between them; yokes limiting the rotation of the levers on the hubs within certain limits; and means to yieldingly hold the levers at their limit of motion in one direction.

13. In an apparatus of the class described, the combination of a plurality of displaceable elements which, by their displacement, indicate a control condition; a plurality of control elements

corresponding to said displaceable elements and selectively settable according to the displacement of the displaceable elements; transmitting means including a shaft, a plurality of hubs connected to the shaft, a plurality of levers mounted on said hubs, certain of said levers 5 cooperating with the displaceable elements and other of said levers cooperating with the control elements, and internal gearing connecting one of said certain levers and one of said other le- 10

vers in pairs for like movement about their hubs; means to shift the shaft step by step to bring pairs of levers successively in cooperation with their related elements; and means to rock the shaft after each step-by-step movement to enable the levers to cooperate with their related elements and transfer the setting of the displaceable elements to the control elements.

GUNNAR NELSON.
